UNITED STATES PATENT OFFICE.

FREDERICK J. CROSS, OF ROCHESTER, NEW YORK, ASSIGNOR TO ROBESON-ROCHESTER CORPORATION, OF ROCHESTER, NEW YORK, A CORPORATION OF NEW YORK.

DESIGN FOR A PLATTER.

Application filed April 11, 1924. Serial No. 9,231. Term of patent 14 years.

To all whom it may concern:

Be it known that I, FREDERICK J. CROSS, a citizen of the United States, residing at Rochester, in the county of Monroe and State of New York, have invented a new, original, and ornamental Design for Platters, of which the following is a specification, reference being had to the accompanying drawing, forming part thereof.

The figure is a plan view of a platter, showing my new design.

I claim:

The ornamental design for a platter, as shown.

FREDERICK J. CROSS.
